UNITED STATES PATENT OFFICE.

HENRY DAVID GUNTHER, OF BROOKLYN, NEW YORK.

CHIROPRACTIC TABLE.

Application filed March 23, 1923. Serial No. 627,112.

To all whom it may concern:

Be it known that I, HENRY D. GUNTHER, a citizen of the United States, residing at 947 Willoughby Ave., Brooklyn, in the 5 county of Kings and State of New York, have invented certain new and useful Improvements in Chiropractic Tables, of which the following is a specification.

This invention relates to surgical appliances, and has special reference to a 10 chiropractic table.

The principal and most important object of the invention is to provide an improved construction of chiropractic table wherein 15 the several parts of the table may be folded so that they may be packed together in the form of a hand satchel, and wherein special provision of novel and improved character is made for the support of the abdomen of 20 the patient during certain manipulations of the lower part of the spine and the parts adjacent thereto, the invention also contemplating the spring supports for this portion of the table which are peculiarly arranged 25 so as not to interfere with the folding of this section when packing the table.

With the above and other objects in view, as will be hereinafter apparent, the invention consists in general of the novel details 30 of construction which are illustrated in one preferred form in the drawings accompanying this specification and forming a part thereof, and which are hereinafter described in detail and specifically pointed out in the 35 appended claims.

In the drawings—

Fig. 1 is a perspective view showing the two sections of the table assembled in the proper position for operation on a patient.

40 Fig. 2 is a detail perspective view showing the section which supports the upper part of the patient's trunk folded.

Fig. 3 is a view similar to Fig. 2, but showing the section which supports the patient's legs and the lower part of the abdomen, the view also showing this section 45 folded.

Fig. 4 is a perspective view of the entire device packed ready for transportation.

50 Fig. 5 is a detail longitudinal section showing the abdominal supporting bracket.

Fig. 6 is a detail view showing portions of the adjacent ends of the sections with the abdominal supporting bracket held entirely 55 by one set of the springs.

Fig. 7 is a view similar to Fig. 6, but showing the second set of springs in use.

Fig. 8 is a detail view on the line 8—8 of Fig. 5.

Fig. 9 is a longitudinal section taken 60 through Fig. 4 with the central portion broken away.

In the construction of the invention there are provided two sections, each of which includes a substantially rectangular angle 65 iron frame 10, to which is pivoted, at each end, a pair of legs 11, these legs being so arranged that they can be folded within the boundaries of the angle iron frame, as disclosed in Figures 2 and 3, or can be extended as in Fig. 1, and secured in extended position by pivoted braces 12 having adjacent their free ends double key hole slots 13, so that they may be slid over butterfly headed screws 14, and then clamped by such 70 screws securely to the leg so that there is no possibility of the table collapsing under 75 the heavy usage to which such tables are subjected.

The upper or head section of the table is 80 provided with a suitable opening 15 formed in the padding 16 wherewith the sections are covered, the opening 15 being for the purpose of permitting the patient to lie face downward with his face in the opening so 85 that he may maintain a recumbent position without turning his head to one side or the other, and yet rest in comfort. Similarly, the other section is provided with an opening 17 for the like purpose of enabling the 90 patient to rest comfortably on the table.

The two sections thus formed constitute practically two shallow trays, and on the lower or foot section of the table, there is provided a set of pins 18 which can be engaged by L-shaped latch members 19 when the two sections are placed together and slid longitudinally, the sections being retained in the longitudinally slid position by a suitable lock 20 when desired. At the 100 upper end of the foot section on the underside of the top 21 of this section, there is provided a pair of aligned brackets 22, to which are pivoted bent arms 23, the arms being so bent as to provide U-shaped portions 24 to enable these arms to pass under the vertical flange of the angle iron frame 10 when the arms are swung outwardly. The free ends of these arms are flattened as 105 at 25, and carried by these free ends is a 110

plate 26, having a padded cover 27 there-over. It will be observed from an inspection of Figures 3 and 5, that these arms and the cover and padded plate may either be 5 folded within the frame 10 as disclosed in Figure 3, or swung outward so that the plate may lie between the two sections of the table when the latter are spaced adjacent each other in alinement as shown in Figures 1, 6 and 7.

Projecting from each side of the bent portion 24 of the arms 23 is a pin 28, and on each of these pins is secured one end of a coiled tension spring 29, the other end whereof is secured to the horizontal flange of the frame 10. Thus these springs, which are of proper length and strength support the plate or bracket formed by the arms 23 and plate 26 in a raised horizontal position, 15 as shown in Fig. 5. Furthermore, on the plate 26 are provided ears 30, to each of which is pivoted an arm 31 carrying on its free end a plunger 32 which is slidably mounted in a sleeve 33 having an eye 34 at 20 one end which fits over a pin 35 projecting from one of the legs 11 of the table. Between the plunger 32 and the eye provided end of the sleeve is a coiled compression spring 36. It will be observed that this 25 construction forms an angle support for the bracket, and that by detaching the eyes 34 from the pins 35, these supports may be folded with the bracket into the space within the frame 10 of this section of the table.

From the foregoing, it will be obvious that either set of springs may be used or, in certain instances, both sets may be used since either set is readily detachable from the bracket. In using this table, the head and 30 foot sections are assembled as in Fig. 1 with the bracket unfolded, as also shown in that figure. The patient may then be placed face down on the table and the lower part of the spine manipulated at the will of the operator, the bracket dropping down under pressure exerted by the operator on that portion 40 of the patient's body which lies above such bracket.

It will be obvious that the foregoing 45 description and the drawings accompanying this specification illustrate merely one preferred form in which the invention may be embodied, and that this invention may be changed and modified in its details, as will 50 be apparent to those skilled in the art, with-

out departing from the material principles herein involved. Accordingly, it is intended that all of such forms as properly come within the scope claimed are to be included.

I claim:

1. In a chiropractic table, a section comprising a frame and legs therefor, an abdominal support pivoted to said section to swing into and out of the space within the frame, said support when swung out of the frame being arranged to normally rise in a horizontal position substantially level with the top of the frame, and spring means having pivotal connection with the abdominal support at one end and with the table section 65 at the other end, one of said connections being readily detachable.

2. In a chiropractic table, a hollow frame, a pair of horizontally alined ears at one end of said frame, arms pivoted in said ears to 70 swing on a horizontal axis into and out of the space within the frame, said arms when swung out of said frame being arranged to lie in a substantially horizontal position, a padded plate supported on the free ends of 75 said arms to constitute an abdominal support when the arms are positioned horizontally on the exterior of the frame, spring means connecting said arms and said frame and yieldably holding the arms in horizontal position, legs supporting said frame, and other spring means connecting said legs and 80 said plate.

3. A chiropractic table comprising a pair 85 of sections each having a hollow frame of substantially the same length and width, said frames being provided with padded tops, foldable legs pivotally mounted within 90 said frames and arranged, when collapsed, to fold within the frames, an abdominal supporting bracket pivotally mounted within one of said frames to swing into position within the frame and into position for use exterior of the frame and 95 substantially level with the top thereof, said abdominal support being arranged to lie between 100 said sections when set up for use, pivot lugs secured to said legs and spring means pivoted to said support and having sockets to engage said lugs for holding the support 105 yieldably in operative position between the said sections.

In testimony whereof I affix my signature.

HENRY DAVID GUNTHER.
